(57) **CLAIM**

The ornamental design for a toilet sensor, as shown and described.

DESCRIPTION

FIG. 1 is a perspective view of a toilet sensor showing the claimed design;

FIG. 2 is a top view of that seen in FIG. 1;

FIG. 3 is a bottom view of that seen in FIG. 1;

FIG. 4 is a left side view of that seen in FIG. 1;

FIG. 5 is a right side view of that seen in FIG. 1;

FIG. 6 is a front view of that seen in FIG. 1; and,

FIG. 7 is a back view of that seen in FIG. 1.

In the drawings, the broken lines depict portions of the toilet sensor that form no part of the claimed design.
